UNITED STATES PATENT OFFICE

JOHN C. STOKES, OF HOUSTON, TEXAS

MEANS FOR SUPPORTING SUCKER-ROD AND PUMP LINES

Application filed November 8, 1927. Serial No. 231,907.

This invention relates to improvements in means for supporting sucker rod and pump lines of oil well pumping equipment and the like.

The primary object of this invention is to provide a simple, practical, and efficient means for relieving the weight of a long string of sucker rods, incident to deep well pumping, so that the sucker rods and their connections are not subject to extreme strains, and for the purpose of relieving the operating mechanism.

In the pumping of oil from deep oil wells, overstressing of sucker rods and the failure thereof, and injury to the operating mechanism are common occurrences. It is fundamentally known that sucker rods of deep well pumping equipment are subjected to combined static and dynamic loads. The static load results from the downward pressure of the column of oil in the tubing above the pump plunger plus the dead weight of the rods themselves. The dynamic load is equivalent to the force necessary to overcome the inertia of the long column of oil and rods that must be accelerated from a position of rest with each upstroke of the pump to a speed consistent with the operation required.

In order to relieve the sucker rods and their connections of some of the weight, I propose to provide means for resiliently supporting the sucker rod line at a plurality of points, at different elevations in the tubing, to provide a distributed support for the long string of pumping equipment. For instance, in a well 5000 feet deep a string of sucker rods weighing 1.6 pounds per foot places a strain of about 8000 pounds on the top joints of the sucker rods, plus the weight of the column of fluid. This weight plus the weight of the column of fluid places a very great strain on the rods and connections during the pumping operation, and it is well known that in very deep wells the rod line will elongate as much as several inches, which of course detracts

from the effective pump stroke of the plunger equipment of the well. In overcoming these disadvantages I provide spring supports for the sucker rod line at different elevations throughout the length of the tubing, in such a relation that the string of sucker rods, and in some instances also the supporting springs may be withdrawn from the tubing. The arrangement is such that without loss and liability of disarrangement of parts the sucker rod line may be lowered into the tubing and the spring supporting means properly locked and applied in place at different elevations in the tubing for the purpose of relieving sucker rod weight therebelow.

Other objects and advantages of the invention will of course be apparent throughout the detailed description.

In the accompanying drawings, wherein for the purpose of illustration are shown preferred and modified forms of the invention,

Figure 1 is a vertical fragmentary sectional view of pump tubing, its reciprocating sucker rod pump line, and the spring means at different elevations in the tubing.

Figures 2 and 3 are transverse sectional views taken substantially on their respective lines in Figure 1 of the drawings.

Figure 4 is a side elevation of a spring cap or collar of one of the sucker rod supporting spring arrangements.

Figure 5 is a side elevation of a spring guide member.

Figure 6 is a plan view of the member of Figure 5.

Figure 7 is a vertical sectional fragmentary view of a modified form of the invention, differing principally over the illustration in Figures 1 to 6, in that different means is provided to automatically lock the sucker rod line at the proper elevation to the spring supporting devices.

Figures 8, 9 and 10 are transverse sectional views taken substantially on their respective lines in Figure 7 of the drawings.

Figure 11 is a fragmentary sectional view taken substantially on the line 11—11 of Figure 8.

Figure 12 is a further modified form of the invention, differing over the forms illustrated in Figures 1 to 11 inclusive, in that special spring supporting arrangements are provided which are withdrawable together with the sucker rod lines through the tubing.

10 Figure 13 is a transverse sectional view taken substantially on the line 13—13 of Figure 12.

Figure 14 is a vertical sectional view of a further modified form of the invention, closely resembling the form of invention illustrated in Figures 12 and 13, but principally differing therefrom in the provision of spring operated pawls or dogs to automatically lock the sucker rod supporting spring arrangements at the different elevations in the tubing.

Figures 15 and 16 are transverse sectional views taken substantially on their respective lines in Figure 14 of the drawings.

25 Figure 17 is a fragmentary sectional view taken through the pawl receiving coupling of the tubing and showing the inside elevation of the pawl carrying member shown in the lower portion of the left hand part of

30 Figure 14.

In the drawings, wherein similar reference characters designate corresponding parts throughout the several views, the letters A, B, C and D may designate the various forms of 35 the invention as illustrated. In the preferred form of invention A the letter D' may designate the tubing ordinarily placed in the well casing, wherein the sucker rod or pump line E is reciprocably disposed, the same having a pump plunger F at the lower end thereof operable in any approved working barrel G. As a novel feature of the invention spring 40 supporting devices H are provided at different elevations throughout the length of the 40 tubing D'.

The tubing line D' may include the ordinary tubing sections 20 connected in communicating alignment with the spring barrel portions 21 by upper tubing coupling 50 sections 22 and lower tube coupling sections 23, as clearly shown in Figure 1. In this arrangement of parts the tubing line D' provides a passageway wherein the pump line E reciprocates, as conventionally known. 55 The spring barrel portions 21 of the tubing line may be slightly enlarged to provide a greater internal diameter than through the normal tubing sections 20.

The lower coupling sections 23, which connect the spring barrels 21 at their lower ends to the tubing sections or the working barrel, as the case may be, are provided with annular shoulders 26 therein facing upwardly into the passageways 27 through the spring barrels 21, on which the lower ends of the spring

arrangements H rest, as will more fully appear hereinafter.

The sucker rod or pump line E includes the conventional sucker rod sections 30, the lowermost of which supports the plunger equipment F, of conventional formation. In the spring barrels 21 the sucker rod sections 30 are connected by special sections 33, each of which is provided with an annular enlargement or shoulder 34, in the upper end of the spring barrel 21. These annular shoulders 34 are of such size that they may be freely drawn through the line of tubing, when the sucker rod line is being withdrawn. However, the shoulders 34 are not all of the same size, but vary in size, from the upper end of the sucker rod line, where the enlargements 34 are of greatest diameter or width, to the lower end of the sucker rod line where the said enlargements 34 are of least width or diameter; the enlargements 34 being graduated with a decreasing width from the upper end of the sucker rod line downwardly, for a purpose which will be hereinafter disclosed.

90 The spring arrangements H are of the same general construction. Inasmuch as they are formed in a practical manner to take a relatively long stroke of the sucker rod line, it is preferred that the same will comprise upper and lower spiral springs 40 and 41, having their proximate ends seated on a tubular spring guide member 42 through which the sucker rod connecting sections 33 freely reciprocates; the guide or spring guide 42 having an annular shoulder 44 formed of lugs 46^a, against which the proximate ends of the springs 40 and 41 engage, as is shown for each of the spring arrangements H in Figure 1 of the drawings. The lower end of the spring 41 seats on the shoulder 26, and the upper end of the upper spring 40 supports a cap or head 45 of sleeve formation. The passageways 47 through the sleeve heads 45 are formed in a gradually decreasing diameter from the upper spring head 45 to the lowermost spring head 45, so that only the respective sucker rod enlargements or shoulders 34 will seat thereon, and so that all of the sucker rod enlargements 34 below the desired one will pass through the passageways 47. With this construction it is perfectly apparent that the sucker rod line may be withdrawn through the various spring devices H, of which the spring heads 45 are a part, but insuring that the sucker rod line when lowering will seat at the proper place upon the respective spring head or cap 45, as shown in Figure 1 of the drawings.

105 The lowermost spring head 45 shown in Figure 1, has a passageway 47 which will permit withdrawal of the lower part of the sucker rod and plunger through the same, and the lowermost enlargement 34 may be drawn readily through all the passageways 47 of the spring heads or sleeves 45 there- 110

above. The various shoulders and seats of the sleeves and spring heads of the parts shown in Figure 1 may be beveled to permit the ready seating and withdrawal of the sucker rod line with respect thereto, without 5 hanging obstruction.

The lugs 46^a permit passage of the medium being pumped through the tubing, and for the same purpose the spring caps or heads 45 are vertically grooved at 50, as shown in Figure 2 of the drawings, and also in Figures 3 and 4.

As to the form of invention illustrated in Figures 7 to 11 inclusive, the same includes 15 many of the features of the preferred form of invention A, and in so far as applicable similar numerals refer to corresponding parts in the forms of invention A and B, except as noted hereinafter.

In the form of invention B the sucker rod line E' has the sucker rod sections 30^a connected by special lengths 33^a, in the spring barrels 21. These special lengths 33^a are of course part of the pumping line, and each of 25 the same intermediate its ends may be enlarged, and through the enlargement is provided a transverse slot or opening 55 wherein a pawl 56 is pivotally mounted, at its upper end, on a pivot pin 57. A spring 58 normally 30 engages against the pawl or dog 56 below its pivot pin 57 to urge the lower end of the dog transversely through the slot 55, as is shown in Figure 7 in a plurality of places.

The spring arrangements H' of the modified form of invention B are exactly the same as the spring arrangement H above described for the preferred form of invention A, except that in place of the spring caps 45 I provide relatively long spring caps or sleeves 60 which 35 rest on the top of the upper springs 40 of each of the spring devices H'. These spring caps 60 are provided with annular recesses 62 facing the passageway 63 thereof, providing upper and lower counter facing shoulders 65 and 66. The height of the annular recesses 45 62 vary for the different spring caps 60 of the different spring devices H', so that the height of the said annular recesses 62 successively increase from the uppermost spring arrangement H' to the lowermost spring arrangement H', where the height of the annular recess 62 is greatest, as can readily be gained from Figure 7 of the drawings. This arrangement of details is provided, inasmuch as the 50 pawls 56 must seat in the respective spring caps or sleeves 60 provided therefor. To this end the pawls 56 are formed to cooperate with the annular seats 62, and the tooth portions of the pawls 56, illustrated by numeral 55 70 in Figure 7 of the drawings, vary in length successively, from the uppermost pawl or dog 56, where the tooth portion 70 is least in height to the lowermost pawl or dog 56, where the tooth 70 thereof is of greatest length. The 60 shoulders 66 in the spring caps 60 are of

course beveled upwardly to engage the pointed teeth ends of the pawls 56 when permitted to do so.

The sucker rod line E' for the form of invention B may be readily withdrawn from the different spring supporting devices H', inasmuch as the teeth 70 on their upper edges are beveled to slide past the upper shoulders 65, and the pawls are retracted to permit the lifting of the sucker rod lines. As the sucker rod line is being lowered through the tubing and the spring devices H', which are in place in the well, it is quite apparent that the lowermost pawl 56, with its long tooth 70, will pass across the annular recess 62 of the spring cap 60 shown in the left hand portion of Figure 7, inasmuch as this particular recess 62 is less in height than the tooth 70 of the pawl 56, and the lowermost pawl 56 cannot enter the recess 62, as is perfectly apparent. In fact, the lowermost pawl 56 can only enter the recess 62 which is specially provided therefor in the lowermost spring arrangement H', as illustrated in the right hand portion of Figure 7 of the drawings.

As is shown in Figures 8 and 10 of the drawings the external surfaces of the spring caps or heads 60 are vertically grooved at 70^a to permit passage of the oil or medium being pumped. The pivot pin 57 for each pawl 56 may be supported in a countersunk relation in the special section 33^a of the sucker rod line, the same having a head 58^a in a counter bore 72 of the portion 33^a, as shown in Figure 11 of the drawings, and a detachable cotter pin 73 seating in a recess 74 provided therein inwardly of the outer confines of the sucker rod section 33^a.

In the form of invention C a tubing line K is provided consisting of conventional lengths of tubing 80 connected by special couplings 81 which provide upwardly facing beveled shoulders 82 projecting inwardly of the passageways 83 through the tubing sections 80, for a purpose to be subsequently described.

It is the purpose of the forms of invention C and D to permit withdrawal of the sucker rod lines, together with the spring arrangement thereon, which seat on the tubing to distribute the load of the sucker rod line at various places along the length of the tubing K.

The sucker rod line L of the form of invention C includes the conventional sucker rod sections 85, the lowermost one of which has the plunger 86 connected therewith, operating in the working barrel 87. At whatever spaced elevations it is desired to distribute a portion of the load of the sucker rod line on the tubing K it is preferred that the sucker rod sections 85 have a special sucker rod insert length 90 which at its upper end clamps an annular projecting washer 91, of ring-shaped formation, in a rigid location on the 130

sucker rod line. At its lower end the special section 90 also clamps an annular ring-shaped seat or washer 92 on the sucker rod line. These annular washers or members 91 and 92 form counter facing abutments or shoulders, as is clearly shown in Figure 12 of the drawings.

The spring arrangements M of the form of invention C each preferably comprises upper and lower spiral springs 95 and 96 seated at their proximate ends against the spaced lugs 97 arranged in an annular sequence on the exterior of a spring guide sleeve 98 similar to that above described for the preferred form of invention, in order to seat the proximate ends of the springs 95 and 96 in a properly guided relation. The upper end of the upper spring 95 seats against the ring-shaped abutment 91, and the lower end of the lower spring 96 rests on the top surface 98 of a slidable follower or sleeve member 100 which is normally urged by the springs 95 and 96 against the washer 92.

When the sucker rod line L is lowered in a pumping operation it is quite apparent that the load thereof will be distributed on the tubing K, at various elevations therealong, incident to the fact that the followers 100 will rest on the shoulders 82 of the tubing couplings 81. As the sucker rod line is elevated, either for removal or during a pumping operation, it is apparent that the springs 95 and 96 of each of the spring arrangements M will force the follower 100 downwardly against its counter facing washer or ring abutment 92 to seat the same thereon.

It is to be particularly noted that for the form of invention C each of the followers or slidable members 100 are of a decreasing width from the uppermost to the lowermost spring arrangement M, so that the follower or member 100 of the lowermost spring arrangement M, illustrated in the right hand portion of Figure 12 of the drawings may readily pass the abutment 82 provided for the members 100 of the spring arrangements M thereabove. This permits a ready withdrawal of the entire sucker rod line, together with the spring arrangements thereon and insures that the followers or members 100 will only seat on the proper shoulders or abutments 82 of the tubing as intended.

In order to permit ready passage of the medium being pumped the ring 91 instead of being annular may have spaced lugs 104 as more particularly shown in the upper right hand portion of Figure 12 of the drawings, and similarly the followers 100 may have a cross sectional appearance such as illustrated in Figure 13, the same being grooved at 105.

In the form of invention D, many of the structural features of the form of invention C are present, and in the forms of invention C and D it is to be understood that like nu-

merals indicate corresponding parts in both of these forms of invention.

In the form of invention D the tubing K' is the same as the tubing K of the form of invention C, except that the tubing couplings 81^a are provided with annular recesses 108 facing in the tubing passageway. The height of these recesses 108 vary from the upper part of the tubing to the lower end thereof, in order to permit a ready passage of the sucker rod line as will be hereinafter set forth.

In the form of invention D the sucker rod line L' is the same as the sucker rod line L of the form of invention C, except that in the form of invention D the spring arrangements M' have the lower followers or members 100^a each provided with diametrically opposed pawls or dogs 110, pivoted on pintles or pins 111 at their upper ends, and the lower portions thereof having springs 112 acting thereagainst, within the outer confines of the members 100^a to force the teeth ends 113 of the said pawls against the insides of the tubing, so that said teeth 113 will seat in the proper recesses 108 of the tubing couplings 81^a, during the lowering operation of the tubing.

In order to insure that the proper pawls or dogs 110 will seat at the proper elevation in the tubing, as the sucker rod line is being lowered, it is intended to vary the length of the pawl teeth or ends 113, so that for the lower spring arrangement M', the said teeth 113 of the pawls 110 are longer than the teeth of the pawls 110 of the spring arrangement M' thereabove. That is to say, the sets M' have the pawl teeth 113 successively increasing in length from the upper set M' towards the lowermost set M', as is illustrated in Figure 14 of the drawings, and this permits the pawls to lock in the proper tubing couplings 81^a. Of course, the teeth 113 are properly beveled on their upper shoulders to retract into the tubing upon an upward pull on the sucker rod line to release the same.

From the foregoing description of this invention it is apparent that practical means has been provided for efficiently supporting the sucker rod line at various points along the tubing, in order that the weight thereof may be distributed and prevent the upper joints and connections of the sucker rods from fracturing under excessive loads. In exemplifying this idea, it may be stated that if the rods below one of the spring arrangements weigh, say 2500 pounds, submerged in the fluid, the spring could have a compressive strength of about 2250 pounds which would not prevent the operation of the rods on the downward stroke, but would carry a great part of the load and be a considerable boost to the operating mechanism on the upward stroke thereof, relieving the pump rod sections of considerable of the 130

weight and reducing the amount of elongation in the line of rods.

The general reference herein to pumping line or pumping string is to be construed as including any reciprocatory pumping mechanism, such as rods, cables, and the like.

Various changes in the shape, size, and arrangement of parts may be made to the forms of invention herein shown and described, without departing from the spirit of the invention or the scope of the claims.

I claim:

1. In pumping equipment a string of tubing, a sucker rod pumping line reciprocable in the tubing, resilient means supporting the sucker rod line upon the tubing and distributing the dead load of the sucker rod line on the tubing, said sucker rod line detachably resting on the resilient means and relatively withdrawable therefrom and from the tubing without interference.

2. In well pumping equipment a line of tubing, a sucker rod line operable in the tubing, spring means yieldably supporting the sucker rod line in the tubing, said sucker rod line being supported upon the spring means in such relation that the sucker rod line may be completely withdrawn from the tubing without interference by the tubing.

3. In oil well pumping equipment a string of tubing, a sucker rod line operable in the tubing, spring devices arranged at different spaced elevations along the tubing for yieldably supporting the sucker rod line, the sucker rod line being so structurally related to the spring devices that the rod line will detachably engage at a particular part only along its length with the respective spring devices so as to permit complete withdrawal of the sucker rod string with respect to the tubing, and without interference by the tubing.

4. In oil well pumping equipment of the class described, a string of tubing, spring devices arranged in the tubing at different elevations, therealong, a sucker rod line operable in the tubing, and means on the sucker rod line for respectively interengaging in a detachable relation with said spring devices to yieldably distribute the weight of the sucker rod line on the tubing adjacent said spring devices.

5. In well pumping equipment a line of tubing, a sucker rod string, spring devices arranged at different elevations in the tubing and supported by the tubing, and enlargements on the rod string for engagement with said spring devices to yieldably distribute the load of the sucker rod line on the tubing line.

6. In well pumping equipment a line of tubing, a sucker rod string, spring devices arranged at different elevations in the tubing and supported by the tubing, enlargements on the rod string for engagement with said spring devices to yieldably distribute the load

of the sucker rod line on the tubing line, said spring devices having passageways therethrough of different sizes for receiving the sucker rod line therethrough, the passageways of the spring devices varying in size from the upper one in which the passageway is largest to the lower one in which the passageway is smallest, and the sucker rod line enlargements varying in size from the uppermost where the enlargement is largest to the lowermost where the enlargement is smallest, in such relation that the enlargements of the sucker rod line may engage with respective spring devices provided therefor and pass freely thru the passageways of all spring devices thereabove to insure complete detachment of the sucker rod line from the tubing and spring devices without interference therewith.

7. In deep well pumping equipment a line of tubing, a sucker rod line, spring devices arranged at different elevations along the tubing, and means on the sucker rod line at different elevations formed to engage with particular spring devices in a detachable relation to obviate removal of the spring devices when the line is removed.

8. In a spring support for pumping lines of well equipment the combination of a pair of compressible spiral springs, and a guide having a sleeve-like body provided with a passageway therethrough and with an annular-like extension externally thereabout between its ends, the ends of said sleeve-like body being inserted into the proximate ends of said springs to align said springs longitudinally with the passageway thru said sleeve.

9. In well pumping equipment the combination of a string of tubing, a pumping line reciprocable in said tubing, upper and lower compression springs, means seating said springs at their adjacent ends in aligning relation, with the pumping string extending thru said springs and thru said means, the lower end of the lower spring having a seat on the tubing, a member seated on the upper end of the upper spring for relative movement along the tubing, and means on the pumping line detachably engageable with the member for resiliently supporting the pumping line on said tubing.

10. In well pumping equipment a string of tubing, a sucker rod line operable in the tubing having a piston operating therein, and spring devices supported in the tubing at spaced points therealong releasably receiving the sucker rod line therethrough, the said sucker rod line having means for engaging the spring devices to support the weight of the sucker rod line at spaced locations therealong upon said spring devices, the sucker rod line extending through all of said spring devices with the piston thereof lying below said spring devices.

11. In well pumping equipment the combi-

nation of tubing within an oil well, a pumping string, and means for resiliently supporting the pumping string in yieldable relation at a plurality of spaced points along the tubing below the ground surface in such relation that the weight of the pumping string is distributed at said plurality of points upon the tubing and in such relation that the pumping string can be completely withdrawn from the tubing without interference by the tubing.

JOHN C. STOKES.
